AUTOMATIC JUICE MAKER

Jurgen Greubel, Eschenhahn, Germany, assignor to Braun
A.G., Frankfurt am Main, Germany

Filed Nov. 25, 1970, Ser. No. 26,153

Claims priority, application Germany July 1, 1970

Term of patent 14 years

Int. Cl. D7—04

U.S. Cl. D89—1 A

Fig 1

Fig 2

Fig 3

Fig 4

Fig 5

Fig 6

FIG. 1 is a front elevational view of an automatic juice maker showing my new design;

FIG. 2 is a right-side elevational view thereof;

FIG. 3 is a rear elevational view thereof;

FIG. 4 is a left-side elevational view thereof;

FIG. 5 is a top plan view thereof; and

FIG. 6 is a bottom plan view thereof.

I claim:

The ornamental design for an automatic juice maker, substantially as shown.
